CONTROL MECHANISM FOR PRESSES

Andrew Eppler, Jr., Lynn, Mass., assignor to
United Shoe Machinery Corporation, Flemington, N. J., a corporation of New Jersey

Application October 11, 1947, Serial No. 779,276

2 Claims. (Cl. 192—131)

1

This invention relates to power-operated mechanisms, and more particularly to control mechanisms therefor. The invention is illustrated herein as applied to a two-station sole-pressing machine although it will be understood that the invention is not limited in its application to machines of the particular type illustrated or to machines for pressing the soles of shoes.

Pressing machines are commonly provided with two hand-control members which require both hands of the operator to operate the mechanism by which the press is closed. By requiring the use of both hands of the operator the danger of injury to his hand by failing to withdraw it completely from between the press members after placing a work piece thereon is eliminated. The present invention is concerned with safety control mechanisms of this general character as applied to two-station machines.

In order to attain maximum production by an operator, pressing machines are commonly made with two stations which are so arranged that when one station is closed, i. e., applying pressure to a work piece between the press members, the other station is open for the reception of a work piece to be operated upon. Each time that the machine is operated one station is opened and the other is closed so that no time is wasted in loading and unloading the machine. To facilitate the operation of such a machine a control member for the mechanism by which the press is operated may be associated with each station so that the operator by standing at either station may readily operate the machine. The control members may operate suitable mechanism such as a half revolution clutch arranged to be engaged upon operation of either control member thereby to open one station of the machine and close the other station.

It is an object of the present invention to provide in a machine of this type, improved safety mechanism which requires the use of both hands of the operator when standing at either station of the machine to start the machine in operation. To this end, and in accordance with a feature of the invention, the machine is provided with three manual control members one of which is located between the stations of the machine and is readily accessible to the operator when standing at either station and the others of which are located one at each side of the machine adjacent to one of the two stations thereof, the control members being so arranged that the machine can be started by manipula-

2

tion of the central control member and either one of the other control members and can be started in no other manner. To insure the maximum safety of the machine the control members are so arranged that no one of them may be tied in any one position and the machine then started by a manipulation of one only of the other members but it is necessary that the central control member and one of the other control members be actually moved each time that the machine is to be started in operation.

The above and other features of the invention, including various details of construction and novel combinations of parts will now be described by reference to the accompanying drawings and pointed out in the claims.

In the drawings, Fig. 1 is a front elevation, partly in section, of one form of machine in which the invention is embodied;

Fig. 2 is an angular view of the central control member and associated mechanism;

Fig. 3 is a vertical section through a portion of the mechanism shown in Fig. 2;

Fig. 4 is a vertical section through the clutch mechanism of the machine, and

Fig. 5 is a section on the line V—V of Fig. 4. As shown in Fig. 1, the machine comprises a base 10 carrying a pair of pressing stations A and B. Each pressing station includes a lower stationary press member or mold 12 with which cooperates a vertically movable press member 14. Each of the press members 14 is guided for vertical movement by a pair of rods 16 which extend upwardly from the lower portion of the base 10. Extending rearwardly and downwardly from each of the press members 14 is a frame 18 the lower end of which carries a pin 20 for one end of a toggle link 22. Each link 22 is connected by a pivot pin 23 to a toggle link 24

40 which is pivoted at 26 to the base 10. When the toggle links are straightened as shown at station A, the upper press member 14 is in pressing relationship with respect to the press member 12 thereby to press or mold a sole S placed therebetween. When the toggle is broken as shown at station B, the upper press member 14 is elevated above the press member 12 so that a work piece may be removed from the lower press member and a new work piece placed thereon.

Carried by the pivot pins 23 and extending toward each other are arms 28 pivotally connected at 30 to a crank arm 32 secured to a shaft 34. When the shaft is rotated 180° from the

position shown in Fig. 1 the toggle at station B is straightened and the toggle at station A is broken so that the press member 14 at station A is elevated and the press member 14 at station B is moved downwardly to act upon the work. For thus turning the shaft 34 a motor 36 is carried by the base of the machine and is connected through reduction gearing 38, 40 and 42 to a gear 44 journaled on the shaft 34. This gear has secured to it, as shown in Fig. 4, a ring 46 forming one element of a rotary pin-type clutch 48. The other element 50 of the clutch is keyed to the shaft 34 and has journaled therein a pin 52 having a cutaway portion 54 projecting into the ring 46. When the pin 52 is turned from the position shown in Figs. 4 and 5, the cutaway portion enters one of a plurality of recesses 56 in the ring 46 thereby to couple the ring to the clutch element 50 causing rotation of the shaft 34.

The pin 52 is acted upon by a spring 58 which tends to move the pin in a counterclockwise direction as viewed in Fig. 5 to engage the clutch elements. The extent of movement of the pin 52 by the spring 58 is limited by a tail 60 formed on the pin which engages the inner surface of the clutch element 46. For holding the pin 52 in the position shown in Fig. 5 when the machine is at rest and to move the pin into this position upon completion of a cycle of operations of the machine which occurs at each 180° of movement of the shaft 34, stops 62, 64 are provided. These stops are located in the path of movement of an arm 66 extending outwardly from the pin 52 so that upon each 180° of movement of the shaft 34 the arm engages one or the other of the stops causing movement of the pin 52 in a clockwise direction against the action of the spring 58 as shown in Fig. 5.

The stop 62 is formed at one end of a lever 68 pivoted on a pin 70 carried by a supporting member 72 which is journaled on a bushing 74 (Fig. 4) surrounding a reduced portion of the shaft 34. The other end of the lever 68 is connected by a link 76 to an arm 78 pivoted at 80 on the supporting member 72, the stop 64 being formed on the arm 78. In order to initiate a cycle of operations of the machine the lever 68 is moved in a counterclockwise direction by means to be described thus moving the stop 62 outwardly of the clutch and this movement is communicated through link 76 to the arm 78 so that regardless of which stop is engaged by the arm 66 it will be moved outwardly thereof permitting engagement of the clutch and operation of the machine. Shortly thereafter the lever 68 is returned to the position shown in Fig. 5 as will be explained so that after the shaft 34 has turned 180° the arm 66 will move into engagement with one of the stops causing the machine to come to rest. In order to stop rotation of the shaft 34 as soon as the clutch is disengaged, the clutch member 50 has secured to it a brake drum 82 around which extends a brake band 84. One end of this band is connected to the pin 70 carried by the supporting member 72 and the other end of the band is connected to one end of a lever 86 pivoted at 88 to the frame of the machine. The other end of the lever 86 is pivotally connected to a block 90 threaded on a screw 92 by which the position of the lever 86 on the pin 88 may be adjusted. When the arm 66 engages one of the stops 62, 64 it tends to move the supporting member 72 in a counterclockwise direction thus causing the brake band 84 to wrap

tightly around the surface of the drum 82 so that the shaft 34 is quickly brought to rest. When the stops 62, 64 are moved outwardly of the clutch the supporting member 72 is moved in a clockwise direction by a spring 94 connected between the lever 68 and the frame of the machine thereby to release the brake band from the drum permitting rotation of the shaft 34. It will be readily seen that the position of the lever 86 may be varied by adjustment of the screw 92 to compensate for any wear of the brake band 84.

For releasing the stops 62, 64, an upwardly extending bar 96 is provided which is pivoted to one end of the lever 68 and is arranged to be moved upwardly by the operator when he desires to start the machine. The upper end of the bar 96 is provided with an L-shaped slot 98 (Fig. 2) through which passes a pin 100 carried by an arm 102 secured to a forwardly and rearwardly extending rockshaft 104. A spring 106 urges the bar 96 to the left, as viewed in Figs. 1 and 2, so that when the parts are in their starting positions the pin 100 is located in the right-hand portion of the slot 98. If now the shaft 104 is turned in a clockwise direction the pin 100 moves upwardly moving with it the bar 96 so that stops 62, 64 are moved outwardly of the clutch which becomes engaged as heretofore explained causing upward movement of one of the press members 14 and downward movement of the other. After the shaft 34 has rotated through a small portion of its 180° of movement the bar 96 is moved to the right so that the vertical portion of the slot 98 receives the pin 100 whereupon the bar 96 is moved downwardly by the spring 94 acting on the lever 68 to move the stops 62, 64 inwardly toward the clutch. It will be noted that the spring 94 is so arranged as to tend to move the lever 68 in a clockwise direction as well as to move the supporting member 72 in the same direction.

For moving the bar 96 to the right as viewed in Figs. 1 and 2 after the machine has started, the following mechanism is provided. Carried by the outer surface of the clutch element 50 is a pair of cams 108 spaced 180° apart in the path of which is a cam roll 110 on the lower end of a release arm 112 pivoted at 114 in the base of the machine. The upper end of the release arm 112 is situated adjacent to the upper end of the bar 96 so that when one of the cams 108 engages the roll 110 causing movement of the release arm 112 in a clockwise direction as viewed in Fig. 1, the arm will engage the bar 96 moving the bar to the right against the action of the spring 106 permitting movement of the stops 62, 64 into operative positions as heretofore explained. In order now to start the machine again after it has come to rest the pin 100 (Fig. 2) must be moved downwardly permitting the bar 96 to be moved so that the pin 100 is again located in the lower right hand portion of the slot 98. This movement of the bar 96 at this time is caused by the spring 106, the release arm 112 being free to permit this movement as the cams 108 are not in contact with the cam roll 110.

In order to rock the shaft 104 thereby to cause operation of the machine, three manual control members 116, 118 and 120 are provided, the control member 118 being located between the two stations of the machine and the members 116, 120 at the left and right sides of the machine respectively. These control members are pivoted to the base of the machine at 117, 119, 121 respectively.

tively and are so arranged, as will be described, that the member 118 and either one of the other members must be moved each time the machine is to be started. This arrangement insures that both hands of the operator will be engaged in starting the operation of the machine thus eliminating the danger that through carelessness he might start the machine before withdrawing his hand from between the press members at that station of the machine which is open. Secured to the rockshaft 104 are upwardly and downwardly extending arms 122, 124 which are connected by links 126, 128 respectively to the lower ends of the control members 120, 116. Thus movement of either one of these control members toward the center of the machine acts to move the rockshaft 104 in a clockwise direction if such movement of the shaft is permitted. In order that the shaft may be thus moved the control member 118 must be simultaneously moved in one direction or the other. The lower end of control member 118, as shown most clearly in Figs. 2 and 3, has a downwardly and forwardly inclined surface 130 terminating in a downwardly facing shoulder 132. The surface 130 is flanked by surfaces 134 which are inclined forwardly and upwardly to provide upwardly facing shoulders 136. The extreme lower end of the control member 118 is provided with a forwardly extending flange 138. Integral with the arms 122, 124 is an arm 140 extending toward the left and carrying in its outer end a detent 142 urged rearwardly by a spring 144 (Fig. 3). The outer end of the detent 142 rides against the adjacent surface of the control member 118 and with the parts in the positions shown in Figs. 1 and 2 the detent is confined against movement between the flange 138 and the shoulder 132 so that the shaft 104 cannot be rocked by operation of either of the control members 116, 120 to cause engagement of the clutch. If, however, the control member 118 is moved either to the right or left the stop 132 will move away from the detent 142 and shaft 104 can then be rocked whereupon the detent will move upwardly over one of the inclined surfaces 134 until it snaps over one of the upwardly facing shoulders 136, thereby locking the shaft 104 against return movement. The shaft 34 now begins to rotate and the release arm 112 operates to move the bar 96 so that the pin 100 enters the vertically extending portion of the slot 98 permitting downward movement of the bar 96 to stop rotation of the shaft 34 after it has completed 180° of movement as heretofore described.

In order now to start the machine again the shaft 104 must be returned to its original position which can only be done by returning the control member 118 to its vertical position thus permitting the detent 142 to move downwardly over the surface 130 and back to the position shown in Fig. 2. This done the machine can be started again by moving one of the control members 116 and the control member 118 to repeat the cycle just described. The control member 118 is normally held in the position shown in Figs. 1 and 2 by a pair of oppositely acting springs 146 which surround a rod 148 pivoted to and extending laterally from the control member 118. These springs act on opposite faces of a downwardly extending projection 150 carried by the base of the machine, the outer ends of the springs acting on collars secured to the rod 148. Regardless of which direction the control member 118 is moved the springs 146 will return it to its central or vertical position when the control member is

released by the operator. The extent of movement of the control member 118 by the operator is limited by stops 151 which depend from the top of the base at opposite sides of the control member. Secured to the arm 102 carried by the shaft 104 is a spring 152 which acts to move the shaft 104 in a counterclockwise direction. Accordingly it will be seen that when the operator removes his hands from the control members these members will automatically return to the positions shown in Fig. 1 and the only movements which the operator must impart to the control members are those which are necessary to start the machine. Inasmuch as it is necessary that the control members be first returned to their original positions before the machine can again be started there is no possibility of the operator tying one of the controls in a fixed position with the expectation that the control of the machine may thereafter be effected by manipulation of only one of the control members.

From the above it will be seen that by a simple arrangement one control member is made to serve both stations of the machine, there being a pair of control members for each station of the machine which must be operated simultaneously each time the machine is to be started, one control member of each pair being common to the two pairs. Thus the operator can control the starting of the machine at either side thereof but must always employ both hands in order to engage the clutch by which the machine is started.

Having thus described my invention what I claim as new and desire to secure by Letters Patent of the United States is:

1. A pressing machine having two stations each of which includes a movable press member, power-operated means for alternately moving said press members into and out of pressing positions, a first control member located centrally of said machine, second and third control members located at opposite sides of the machine, mechanism operated only by movement of either said second or said third control member from predetermined starting positions for rendering said power-operated means operative, an arm connected to said second and third control members for movement thereby when the control members are moved, a pin carried by said arm, a stop carried by the first control member cooperating with said pin with the first control member in one position to prevent movement of the second and third control members away from starting positions, and other stops carried by the first control member cooperating with said pin with the first control member out of said one position to prevent return movement of the second and third control members to starting positions.

2. Starting mechanism for a two-station pressing machine comprising a clutch, mechanism operative upon each engagement of the clutch for opening one station of the machine and closing the other station thereof, means for automatically disengaging said clutch after each operation of said mechanism, a first manual control member convenient to both stations of the machine, a second manual control member convenient to one station only of the machine, a third manual control member convenient to the other station only of the machine, mechanism operated only by movement of said second or said third control member from predetermined starting positions for causing engagement of said clutch, an arm connected to said second and third control members for movement thereby when the control

members are moved, a pin carried by said arm, a stop carried by the first control member co-operating with said pin with the first control member in one position to prevent movement of the second and third control members away from starting positions, and other stops carried by the first control member cooperating with said pin with the first control member out of said one position to prevent return movement of the second and third control members to starting positions.
